UNITED STATES PATENT OFFICE.

CHARLES MYRON JONES, OF NORTH YAKIMA, WASHINGTON.

WRENCH.

1,326,454.

Specification of Letters Patent. Patented Dec. 30, 1919.

Application filed April 24, 1919. Serial No. 292,297.

To all whom it may concern:

Be it known that I, CHARLES MYRON JONES, a citizen of the United States, residing at North Yakima, in the county of 5 Yakima and State of Washington, have invented certain new and useful Improvements in Wrenches; and I do declare the following to be a full, clear, and exact description of the invention, such as will enable others 10 skilled in the art to which it appertains to make and use the same.

This invention relates to improvements in wrenches, particularly that type adapted for use in removing grease cup caps.

15 The primary object is to provide a simple and improved device of this character which will be especially valuable in removing caps from grease cups so positioned that the operator cannot reach them without the aid 20 of a tool.

Another object is to provide a simply constructed and highly efficient device of this character which may be easily operated and will eliminate the necessity of having 25 soiled hands after refilling grease cups.

With these and other objects in view, my invention resides in certain novel features of construction, and in the combination and arrangement of parts as will be more fully 30 described and claimed, the descriptive matter being supplemented by the accompanying drawing in which:—

Figure 1 is a side elevation of the wrench applied to a grease cup cap, and

35 Figs. 2, 3 and 4 are sectional views taken on the lines 2—2, 3—3, and 4—4 of Fig. 1 in the directions indicated by the arrows.

As clearly illustrated in the accompanying drawing, my device includes a handle 1 which is preferably cylindrical in shape and 40 is formed from any suitable material, said handle having its surface knurled.

A plurality of cast spring arms 2 extend from one end of the handle 1, each of said 45 arms having one end secured in the handle by any suitable means, preferably cast with the handle which is solid. The outer free ends 3 of the arms 2 are beveled outwardly for a purpose to be fully set forth in the 50 following description.

For the purpose of providing means for gripping the flange R of the cap C of a grease cup G to remove said cap each arm 2 is provided on its inner face with a longitudinally 55 extending recess 4, each of which is formed by oppositely beveling the arm at points ad-

jacent the beveled ends 3, the bevels 5 converging toward the longitudinal axis of the implement. The bevels 5 are slightly concave so as to give the recess a hook 6 to engage the flange R and retain it in its proper position for removing the cap.

When using this cap remover the operator grasps the handle 1 and forces the beveled ends 3 to slide over the rim "R" of the cap 65 to be removed. Upon completion of this operation the hooks 6 are securely holding the cap from pulling free from the arms and the recesses 4 are engaged with the serrations on the flange so as to prevent the arms from 70 slipping without removing the cap.

The resiliency of the arms 2 is materially increased by cutting away a portion of the metal on their inner faces at points near the handle 1. In cutting out the above named 75 portion the arms are cut transversely from their inner faces to a point approximately one-half the diameter and then cut away longitudinally, gradually tapering to the inner faces of said arms to points substantially midway their lengths. By increasing the resiliency in this manner, the degree of spreading is increased, so that various sized 80 caps may be removed with the same wrench.

In order to assure positive engagement of 85 the teeth and cap flange, I have provided a ring 7 which is adapted to slide over the arms 2 and contract the free ends around the cap. The inner periphery of the ring is oppositely beveled to form a continuous V- 90 shaped rib 8 adapted to engage serrations 9 on the outer faces of the arms 2. The pressure of the biting teeth 4 on the flange R may be varied by adjusting the ring in the 95 serrations.

Although I have described the ring 7 as having a V-shaped rib 8 to engage the serrations, I wish it understood that I may eliminate the rib and use a plain ring.

From the foregoing description, taken in 100 connection with the accompanying drawings, the construction and operation of the invention will be readily understood without requiring a more extended explanation.

Various changes in the form, proportion 105 and the minor details of construction may be resorted to without departing from the principle or sacrificing any of the advantages of the claimed invention.

I claim:

110 1. A grease cup cap remover comprising a hand grip, a plurality of diverging arms

on said hand grip, movable toward and from the longitudinal axis of the implement, each of said arms being provided with a longitudinally extending outwardly beveled face 5 at its end to guide the ends of the implement over a cap, and each of said arms being provided with a pair of concave recesses converging toward the longitudinal axis of the implement to form a longitudinally extending biting tooth, said tooth being curved longitudinally and adapted to receive the flange on the grease cup cap.

2. A grease cup cap remover comprising a hand grip, a plurality of diverging resilient arms extending from one end of said 15 hand grip, said arms having portions cut away from their inner faces at points near the hand grip to give them increased resiliency, each of said arms being provided

with a longitudinally extending outwardly beveled face at its end to guide the ends of the implement over a cap, each of said arms being provided with a pair of concave recesses converging toward the longitudinal axis of the implement to form a longitudinally extending biting tooth, said tooth being curved longitudinally and adapted to receive the flange, of a grease cup cap, said arms being serrated on their outer faces, and a ring slideable over said arms and having 25 its inner periphery oppositely beveled to form a continuous V-shaped rim to engage the serrations and hold the arms contracted upon the cap flange.

In testimony whereof I have hereunto set 30 my hand.

CHARLES MYRON JONES.
